ROTATABLE CONCRETE MIXING DRUM WITH IMPROVED DISCHARGE PERFORMANCE

Louis G. Hilkemeier, Plainfield, N.J., assignor to Worthington Corporation, Harrison, N.J., a corporation of Delaware

Application October 28, 1957, Serial No. 692,696

2 Claims. (Cl. 259—161)

This invention relates to an improved inclined rotatable mixing drum of the type used in transit concrete mixers, and more particularly to a mixing drum of this type having a new and novel shape which enables the concrete to be discharged therefrom at a faster and thus more satisfactory rate.

Numerous attempts have been made, and are still being made, to increase the mixing drum discharge rate so that the time consumed by this operation is lessened, and the transit mixer thereby capable of making more trips during the course of a day's operation. These attempts have resulted in proposals of what can be termed "discharge aiding" devices, as for example, the vibration elements taught in application Serial No. 669,382, filed July 1, 1957 by the present inventor, and the frusto-conical member taught in U.S. Patent 2,805,053 issued on September 3, 1957, each of which serves to facilitate drum discharge.

While these "discharge aiding" devices to a large degree solve this vexing problem, their application to mixing drums having the traditional frusto-conical shape from front end to rear discharge end, as is currently the universal practice, is an unfortunate contradiction as well as a needless limitation to their maximum operating potential, for this said traditional frusto-conical drum shape is itself a major factor contributing to clogging in the discharging concrete, and thus to the slow, unsatisfactory discharge rate of the drum.

Undoubtedly this shape for the drum is being perpetuated by a desire to have, on the one hand, a maximum capacity interior mixing area, and on the other hand, a shape least susceptible to spillage. However, I have found that without resorting to any "discharge aiding" devices, but only by departing from this traditional shape universally applied to mixing drums, that a drum can be produced which has an acceptable high capacity-low spillage characteristic, and at the same time a faster and completely satisfactory discharge rate.

With the specific object in mind of improving the discharge rate of the inclined rotatable type concrete mixing drum, I therefore propose herein a new and novel shape for these drums.

More specifically, in the present invention I propose that the shape of the drum, instead of being frusto-conical from front end to rear discharge end, be frusto-conical in shape from its front end for only a prescribed portion of its axial length, and then be completed by a substantially cylindrical section which has the drum discharge opening provided in its remote end. In this shape, the drum has an acceptable high capacity-low spillage characteristic by reason of the front frusto-conical drum section, and in addition when the concrete flows to discharge through the said rear cylindrical drum section, there is no squeezing of and consequent clogging in the concrete as occurs in present drums, where the rear drum portion is frusto-conical and thus has a progressively narrowing passageway to the drum discharge opening.

This improved shape for inclined rotatable concrete

2

mixing drums will be better understood from the accompanying specification and the single figure drawing forming a part thereof, in which there is shown a partly broken away side view of this type of concrete mixing drum having this improved shape.

In the drawing, the rotatable mixing drum 1 is shown in the inclined angular position it would occupy when mounted on a transit concrete mixer. The mobile unit or truck, mounting frame, means for rotatably mounting the drum, driving means to rotate the drum in the directions for "mix" and "discharge" indicated in the drawing, and other associated equipment such as discharging chutes have been omitted from the drawing since they do not form an essential part of the present invention. As has been indicated, the present invention concerns only an improved shape for the drum, which shape more particularly permits a faster rate of discharge than is possible using the completely frusto-conical shape now being almost universally employed in the concrete mixing art.

20 To apply this improved shape to the drum 1, the said drum is formed in two sections; a front section 2 and a rear section 3. These two sections are connected end-to-end to each other at the point indicated at 4, the connection being accomplished by any well known manner, such as by welding. A discharge opening 5 for the drum 1 is provided in the end of the rear drum section 3, and axially spiraled mixing blades 6, 7 originating in this said opening are mounted on the interior walls of the connected drum sections 2 and 3 extending the entire axial length of the drum 1.

Referring specifically to the shapes of the respective drum sections: the front section or section 2 is generally frusto-conical, and as such provides the drum 1 with an interior mixing area which has an acceptable high capacity-low spillage characteristic; and the rear section or section 3 is generally cylindrical, and as such provides the drum 1 with a wall parallel to the drum axis from the mixing area of the front drum section 2 to the drum discharge opening 5 in the end of the rear drum section 3.

40 To facilitate in the charging of the drum 1, and to increase the load carrying capacity thereof, a charging cone 10 is suitably welded centrally of the first turns of the mixing blades 6, 7 in the drum discharge opening 5. According to the well known operation of this charging cone 10, materials are inserted into the drum through the charging cone axial opening 11 which permits bypassing the first coils of the mixing blades 6, 7 and thus a faster charging operation. During drum discharge, the mixing blades 6, 7 convey the concrete from the drum mixing area to the drum discharge opening 5, and thus the concrete is forced through the passageway 12 defined by the outer periphery of the charging cone 10 and the wall of the rear drum section 3, and at this point is most susceptible to clogging which causes a slow and unsatisfactory discharge rate.

55 In the present invention, however, because the wall of the rear drum section 3 is parallel to the axis of the drum 1 instead of converging inwardly towards the drum axis as would be the case if this section of the drum conformed to the frusto-conical shape of the front drum section 2, there is no substantial opposition to the free and smooth discharge of the concrete as it passes through the passageway 12. Thus, I have found that a drum shaped as in drum 1, and merely by reason of this shape, has a discharge rate which is satisfactory for use on transit concrete mixers.

60 In addition to not opposing the discharge flow, the rear drum section 3 is necessarily wider than a tapering rear drum section of a traditional completely frusto-conical shaped drum of comparable size, and thus allows making the first coils of the spiraled blades 6, 7 slightly larger in height to give a larger pushing surface at the discharge

end of the drum 1 which also appreciably increases the drum discharge rate.

In determining the proper lengths for the respective drum sections 2 and 3, due consideration must be given to the capacity required in the drum, the rate of discharge required of the drum, and also the numerous factors which may contribute to drum leakage, as for example, whether the concrete is high or low slump, the usual inclines traversed by the transit mixer while traveling to the job site, etc. It is therefore difficult to prescribe one ratio for these lengths fitting all situations other than to state that I have found that the most versatile drum having the improved shape herein described is obtained when the length of the rear drum section 3 is approximately one-tenth the length of the front drum section 2, or as these lengths are represented in the drawing, the line B—C 15 is one-tenth that of line A—B.

It will be understood of course that the invention is not intended to be limited to the ratio of 1:10 for the drum sections, or is it to be limited to the exact shape for the mixing drum sections shown herein, but that wide modifications can be made in each within the invention as defined by the claims.

What is claimed is:

1. A mixing drum comprising a hollow front drum section and a hollow rear drum section connected to each other and rotatable about its axis, an end opening in the rear drum section for discharging the drum contents, and a plurality of axially spiraled mixing blades each of which originate in said end opening and extend continuously inwardly therefrom along the interior wall of said rear and front drum sections, said front drum section having a wide base and sides tapering inwardly towards the drum axis in the direction of the rear drum section defining a substantially frusto-conical shaped mixing area of relatively large capacity, and said rear drum section being

substantially cylindrical in shape having sides parallel to the drum axis extending from the end of the tapering sides of said front drum section to the end discharge opening, whereby clogging in the materials flowing to the said end discharge opening is minimized.

2. A mixing drum comprising a hollow front drum section and a hollow rear drum section connected to each other and rotatable about its axis, an end opening in the rear drum section for discharging the drum contents, a plurality of axially spiraled mixing blades each of which originates in said end opening and extends continuously inwardly therefrom along the interior wall of said rear and front drum sections, and a charging cone disposed centrally of the mixing blades in said end opening, said front drum section having a wide base and sides tapering inwardly towards the drum axis in the direction of the rear drum section defining a substantially frusto-conical shaped mixing area of relatively large capacity, and said rear drum section being substantially cylindrical in shape having sides parallel to the drum axis extending for the axial length of said charging cone from the end of the tapering sides of said front drum section to the end discharge opening, whereby clogging in the materials flowing between said charging cone and the interior wall of said rear drum section to the said discharge opening is minimized.
